US00D796775S

(12) **United States Design Patent** (10) Patent No.: **US D796,775 S**
 Amoako-Poku et al. (45) Date of Patent: ** Sep. 12, 2017

(54) **CONFECTION**

(71) Applicant: **INTERCONTINENTAL GREAT BRANDS LLC**, East Hanover, NJ (US)
 (72) Inventors: **Francis Amoako-Poku**, Whippany, NJ (US); **Susan Pettigrew**, Whippany, NJ (US); **Doris Tancredi**, Whippany, NJ (US); **Zi Yang**, Whippany, NJ (US); **Kishor Kabse**, Whippany, NJ (US); **Atsushi Ueminami**, Kanagawa (JP)

(73) Assignee: **INTERCONTINENTAL GREAT BRANDS LLC**, East Hanover, NJ (US)

(**) Term: **15 Years**

(21) Appl. No.: **29/557,231**

(22) Filed: **Mar. 7, 2016**

(57) **CLAIM**

We claim, the ornamental design for a confection, as shown and described.

DESCRIPTION

FIG. 1 is a perspective view of a confection, showing our new design in an exemplary embodiment;

FIG. 2 is a side elevation view of the embodiment shown in FIG. 1;

FIG. 3 is another side elevation view of the embodiment shown in FIG. 1;

FIG. 4 is a front elevation view of the embodiment shown in FIG. 1;

FIG. 5 is a rear elevation view of the embodiment shown in FIG. 1;

FIG. 6 is a top plan view of the embodiment shown in FIG. 1;

FIG. 7 is a bottom plan view of the embodiment shown in FIG. 1;

FIG. 8 is a perspective view of a confection, showing our new design in another exemplary embodiment;

FIG. 9 is a side elevation view of the embodiment shown in FIG. 8;

FIG. 10 is another side elevation view of the embodiment shown in FIG. 8;

FIG. 11 is a front elevation view of the embodiment shown in FIG. 8;

FIG. 12 is a rear elevation view of the embodiment shown in FIG. 8;

FIG. 13 is a top plan view of the embodiment shown in FIG. 8;

FIG. 14 is a bottom plan view of the embodiment shown in FIG. 8;

FIG. 15 is a perspective view of a confection, showing our new design in another exemplary embodiment;

FIG. 16 is a side elevation view of the embodiment shown in FIG. 15;

FIG. 17 is another side elevation view of the embodiment shown in FIG. 15;

FIG. 18 is a front elevation view of the embodiment shown in FIG. 15;

FIG. 19 is a rear elevation view of the embodiment shown in FIG. 15;

FIG. 20 is a top plan view of the embodiment shown in FIG. 15; and,

FIG. 21 is a bottom plan view of the embodiment shown in FIG. 15.

The broken lines in FIGS. 15-19 and 21 illustrate portions of the confection that form no part of the claimed design.

The dash-dot lines are boundary lines delimiting claimed from unclaimed subject matter.
